FRANK HOPKINSON, OF LONDON, ENGLAND

SEPARATING AND GRADING APPARATUS

Application filed November 3, 1928. Serial No. 317,033.

This invention relates to improvements in the separation or grading of solid materials by the action of an air blast.

In apparatus of this character the material to be separated is fed upon a reciprocating support through which a blast of air is passed. The lighter constituents of the material are carried upward by the air blast into a large collecting chamber, while the heavier constituents are caused by the reciprocating movement of the support to move along the latter. The greater part of the lighter constituents carried upward by the air blast fall out of the air current in the collecting chamber and are trapped in suitable pockets, but it is impossible to ensure that all of the finest particles are deposited, and, in order to avoid nuisance, the air blast is not permitted to escape to the atmosphere but is kept in circulation through the apparatus. To this end the collecting chamber has a duct extending across its upper part and this duct is connected with the intake of the fan which creates the air blast, so that the air is withdrawn from the chamber through the duct and returned to the chamber through the reciprocating support.

It has been found that the ducts of apparatus of this character between the chambers and the fan require frequent cleansing or repair, in which case it becomes necessary to temporarily discontinue the return of the air stream to the fan and to allow the air blast to escape from the upper portion of the chambers and to permit the fan to take in fresh air from the atmosphere. While the return of the air stream to the fan is discontinued the chambers act as baffles which hinder the discharge of the spent blast from the upper part of the chamber and not only cause back pressure but also cause deflections of the air current which stir up the deposited dust and carry it into the atmosphere.

The difficulty just referred to is overcome by the present invention by providing the portion of the duct which is located within the collecting chamber with movable portions which may be moved into such position that they afford a vertical passage through the duct for free traverse of air during the period

that the return of the air stream to the fan is discontinued.

The air duct may be constructed in a form of a box-like channel having opposite walls, preferably top and bottom walls, hinged to the other walls and made in one or more parts in the form of flaps. The hinged flaps may be operated in any suitable manner, for instance by chains, and devices may be provided whereby the flaps may be locked in any desired position, so that one or more may remain more or less open.

To prevent the re-entrainment by the air stream of any dust which may have settled in the said box-like channel, the invention provides a number of baffles spaced at intervals throughout the entire length of the box. The baffles may, if desired, be fixed to the bottom closure members at right angles thereto and in staggered relationship to one another.

Suitable arrangements are made in the inlet duct to the fan for closing this against the return air stream and adjustable arrangements are also provided whereby the fan can obtain fresh supplies of air from the atmosphere when the return duct is inoperative.

The accompanying drawings illustrate one construction of apparatus embodying the present invention, Fig. 1 being a vertical longitudinal section of the apparatus; Fig. 2 a transverse section on line 2-2 of Fig. 1; Fig. 3 an enlarged view of the air duct shown in Fig. 2; and Fig. 4 a sectional plan view of a section of the air duct shown in Fig. 3.

In these drawings, *a* is the suction fan, *b* the collecting or expansion chamber, *c* the separating table for receiving material containing dust, *d* the relatively narrow passage leading from the separating table to the expansion chamber, *e* dust pockets at either side of this passage, *f* conveying screws for withdrawing the dust collected in these pockets, *g* baffles which may or may not be provided within the expansion chamber to reduce the cross sectional area of this chamber locally, and *i* the cover over the open top of the expansion chamber.

The foregoing parts constitute a well-known form of apparatus.

According to the present invention, that part of the air duct leading from the expansion chamber *b* to the suction fan chamber *j* which lies within the expansion chamber and is indicated at *l*, is formed with hinged walls or flaps which can be opened or closed to any desired extent for the purposes hereinafter specified.

As shown in the drawings, the bottom of the air duct *l* is constituted by two flaps *m* hinged to the side walls *l*⁰ of the duct, while the top of the duct is constituted by two similarly hinged flaps *n*. These flaps are operable as by means of chains, so that they can be opened or closed to any desired extent. For example, as shown in Fig. 3 with respect to the top flaps *n*, each flap may be separately raised as by a chain *o* from the closed position shown in dotted lines in Fig. 3, so that they can be opened partially as shown in that figure, or completely so that the flaps *n* lie in the same plane as the side walls *l*⁰ of the air duct. Or the flaps can be operated in pairs by means of a single chain *p*, as shown in Fig. 3 with reference to the bottom flaps *m*.

In the normal working position the bottom flaps *m* are closed, as shown in dotted lines in Figs. 2 and 3, and the upper flaps *n* are opened either wholly or partially, so that the stream of air passing upwards from the expansion chamber changes its direction in passing into the air duct *l* through its upper opening.

With the bottom flaps *m* opened wholly or partly, as shown in full lines in Figs. 2 and 3, and the top flaps closed as shown in dotted lines in these figures, the air which enters the duct *l* from below cannot escape to the atmosphere, but passes along the duct to the downtake *q* leading to the fan chamber *j* and a circulation of air is maintained. This circulation can be varied to a greater or less extent by means of a closure device such as a series of louvres *r* operable by means of suitable gear and adapted to close the inlet end of the downtake *q* completely or partially.

With the bottom and top flaps both completely opened so that they lie in the plane of the side walls *l*⁰, the air escapes freely from the expansion chamber *b* to the atmosphere with minimum resistance.

With the bottom and top flaps both partly opened, part of the air will return to the fan and part escape directly to the atmosphere from the expansion chamber, the proportion being determined by the extent to which the flaps are opened and being further determinable by regulation of the louvres *r*.

When the louvres *r* are completely closed against the return of the air stream from the duct *l* to the fan chamber *j*, the fan can obtain a supply of air direct from the atmosphere by opening to any desired extent a regulating shutter or shutters *s* provided in a wall of the fan chamber *j*.

When the flaps of the air duct *l* are in the

position for normal working, it is desirable that dust carried by the air into or previously deposited from the air within the duct *l*, should be arrested or its re-entrainment in the air prevented, and this is effected by providing transverse baffles within the duct. As shown in the drawings, these baffles are constituted by plates *t* (see Figs. 3 and 4) extending in opposite directions inwardly from the lower flaps *m* and relatively staggered, so that the air in its passage through the duct *l* is constrained to follow a tortuous course changing direction repeatedly, with the result that dust carried by it tends to be arrested by the baffles *t* and deposited on the floor of the duct, and any dust already deposited therein is not swept away and re-entrained by a high velocity stream of air in the duct.

The dust collected in the duct *l* may be removed by opening the flaps *m* to discharge the accumulated dust into the dust ducts *e* from which it is removed by screw conveyors *f*, the flaps or baffles *g* being then turned inwardly so as to deflect the dust from falling into the passage *d*, and for this and other purposes the flaps *g* may be made extensible as indicated in Fig. 2. Alternatively, a displaceable lid or lids may be provided for the top of the passage *d*.

The material containing dust may be received from any source and delivered upon the separating table *c*, the heavier dust will collect in the chamber *b*, while the lighter dust will circulate.

Having thus fully described the nature of the said invention and the best means I know of carrying the same into practical effect, I claim:

1. In apparatus of the kind referred to, a dust collecting chamber open to the atmosphere at its upper part, a duct extending across the chamber and adapted to receive air from the chamber, means for introducing a blast of air into the chamber, and removing the spent blast through said duct, said duct having movable portions adapted when moved to open a vertical passage through the duct.

2. In apparatus of the kind referred to, a dust collecting chamber, an air-return duct extending across said chamber, pivoted flaps forming the top of said duct, pivoted flaps forming the bottom of said duct and means whereby the said flaps can be opened and closed.

3. In the apparatus claimed in claim 1, transverse baffles in the duct.

4. In apparatus of the kind referred to, a dust collecting chamber, an air-return duct extending across said chamber, pivoted flaps forming the top of said duct, pivoted flaps forming the bottom of said duct, means whereby the said flaps can be opened and closed and transverse baffles in the said duct.

5. In the apparatus claimed in claim 1,

baffle plates within the duct extending in opposite directions from the walls of the duct in staggered relationship.

6. In apparatus of the kind referred to, a dust-collecting chamber, an air-return duct extending across said chamber, pivoted flaps forming the top of said duct, pivoted flaps forming the bottom of said duct, means whereby the said flaps can be opened and closed and baffle plates within the said duct extending in opposite directions inwardly from the walls of the duct in staggered relationship.

7. Apparatus of the kind referred to, comprising a dust collecting chamber, dust pockets formed in the bottom of the said chamber, means for removing dust from the said pockets, an air-return duct extending across the said chamber, means for discharging dust from the bottom of said duct and baffles in the said chamber adapted to be turned into the path of dust falling from the said duct whereby such dust is guided into the said pockets.

25 In testimony whereof I have signed my name to this specification.

FRANK HOPKINSON. [L. S.]
